COUPLER CARRIER AND STRIKING
CASTING

Donald S. Barrows, Rochester, N. Y., assignor to
The Symington Company, New York, N. Y., a
corporation of Maryland

Application November 12, 1928, Serial No. 318,763

16 Claims. (Cl. 213—50)

This invention relates to draft rigging and more particularly to a coupler carrier or sill tie casting and associated striking casting, especially adapted for use with a coupler having an enlarged butt such as a swivel butt coupler.

The principal object of my invention, generally considered, is to provide an associated striking casting and sill tie member or coupler carrier adapted for connection through the associated sills of the car so that they function as a combined striking casting and sill tie member, said sill tie member being adapted to support an associated carrier block and having a tie portion so formed that the carrier block may be inserted and removed even while the associated coupler is disposed thereabove.

Another object of my invention is to provide a coupler carrier or sill tie casting formed with horizontal and vertical webs adapted for connection respectively to the lower flanges and webs of the associated draft sills, the tie portion of said casting being off-set or bowed downwardly at its intermediate or central portion to facilitate insertion and removal of the butt of an associated coupler.

A further object of my invention is to provide a coupler carrier or sill tie casting adapted for connection to the lower portions of associated draft sills for supporting a carrier block therebetween, the tie portion of said casting comprising vertical transverse webs or flanges connected by a horizontal web which is discontinued along a portion of the tie member to provide an aperture for insertion and removal of the carrier block from below, even while the associated coupler is disposed above the sill tie casting, means being provided for normally locking said carrier block in place when the coupler is in position by closing the aperture in the bottom of the casting.

Other objects and advantages of the invention relating to the particular arrangement and construction of the various parts will become apparent as the description proceeds.

Referring to the drawings illustrating my invention, the scope whereof is defined by the appended claims.

Figure 1 is a vertical longitudinal sectional view of one embodiment of my sill tie casting and associated striking casting assembled with associated sills and cheek plates, on the line 1—1 of Fig. 2, looking in the direction of the arrows, the associated coupler being diagrammatically indicated by dot and dash lines.

Figure 2 is a front elevational view of the sill

tie and striking castings of Figure 1, one portion thereof being shown in transverse section on the line 2—2 of Fig. 1, looking in the direction of the arrows.

Figure 3 is a fragmentary horizontal sectional view on the line 3—3 of Figure 2, looking in the direction of the arrows.

Figures 4 and 5 are views corresponding respectively to Figures 1 and 2 but showing a modification, said views being respectively on the line 4—4 of Fig. 5, and partly on the line 5—5 of Fig. 4, looking in the directions of the arrows.

Figure 6 is a fragmentary sectional view on the line 6—6 of Figure 5, looking in the direction of the arrows.

Figure 7 is a fragmentary front elevational view corresponding to Figure 5 but showing a modified locking device or carrier block retainer.

Figure 8 is a transverse sectional view on the line 8—8 of Figure 7, looking in the direction of the arrows.

Referring to the drawings in detail, like parts being designated by like reference characters, and first considering the embodiment of my invention illustrated in Figures 1 to 3 inclusive,

there are shown a pair of draft or center sills 1, generally U shaped in section, with vertical webs 2 and upper and lower outstanding flanges 3 and 4 respectively. Associated with the ends of said sills 1 is a striking casting or coupler stop member 5 particularly designed to avoid the necessity of coping the sills. For that purpose, said casting comprises a pair of vertical webs 6 extending between the sills 1 and engaging the inner surfaces of webs 2 thereof, being connected to said webs preferably by rivets 7. Connecting the upper edges of the webs 6 is a top plate or roof portion 8 which is extended over the upper flanges 3 of the sills and adapted for connection thereto. The rearward portion of the top web 8 is preferably formed narrow enough to fit between the webs 2 of the sills and depressed in elevation as indicated at 9 so that the upper surface thereof is flush with the top of sills 1, whereby it is adapted for connection with the usual cover plate (not shown). Said casting 5 also has a front wall or web 10 against which the horn of the associated coupler 11 is adapted to engage and limit rearward movement thereof, said web 10 being preferably extended laterally beyond the webs 2 of the sills as indicated at 12 and between said webs being preferably thickened to provide ample buffering capacity. In order to additionally strengthen the web 10, the same is preferably reinforced by a plurality of longi-

tudinally extending webs 13 and a horizontal web 14, said webs 13 rearwardly of the web 14 tapering until they finally merge into the upper web 9. In a similar way the connecting webs 6 5 rearwardly of the last rivet 7 taper until they finally merge into the web 9.

Connecting the lower portions of the sills 1 at each end thereof is a sill tie casting 15, which casting is preferably formed with longitudinally 10 extending webs or flanges 16 corresponding with the flanges 6 of the striking casting and adapted for connection to the webs 2 of the sills by a plurality of rivets 17. Extending outwardly from the webs 16, so as to underlie the flanges 4 of 15 the sills, are webs 18 adapted for connection to said flanges in any desired manner as by means of rivets 19. As with the striking casting 5, the sill tie casting 15 preferably has a front web 20 which is extended laterally outwardly beyond the 20 webs 16 and tapered between the webs 18 and the upper edges of the webs 16, as indicated at 21, for rigidifying the connection therebetween.

In addition to the front web 20, the tie portion 22 of the casting 15 comprises a rearward 25 web 23 parallel with the web 20 and a lower horizontal web 24 connecting the lower edges of the webs 20 and 23. Said horizontal web at its central portion is preferably rigidified by an upstanding central flange 25.

30 In addition to the connecting web 24 and flange 25, the tie portion 22 is also provided with horizontal carrier block supporting webs 26 preferably rigidified beneath the webs 16 by depending flanges 27 and apertured beneath the 35 rivets 19 as indicated at 28 to facilitate driving said rivets. Said webs 26 are continued inwardly a short distance to underlie the ends of the carrier block 29 as indicated at 30, said carrier block, however, not being directly supported on 40 said extensions 30 in the present embodiment, but resting on a supporting plate 31, which also serves as a retainer or locking means for the carrier block 29 by closing the openings 32 between the webs 20, 23 and 24, thereby preventing 45 removal of the carrier block 29 as long as the associated coupler 11 is in place. Said retainer or supporting plate 31 may be held in place in any desired manner as by means of a cotter or the like 33 extending through registering apertures 34 and 35 in the web 26 and plate 31 respectively.

50 In order to facilitate insertion and removal of the block through one of the apertures 32 in the bottom of the sill tie casting 15, said carrier block preferably has the lower web 36 omitted and the side webs 37 bowed upwardly as indicated at 38 adjacent the center thereof, which construction also lightens the weight of the 55 block. In addition to the webs mentioned, said block also preferably has an upper web 39, the central portion 40 of which is preferably thickened and raised slightly above the end portions and normally carries a U shaped wear plate 41. In order to facilitate the insertion and removal 60 of the butt of the coupler 11, which in the present embodiment is illustrated as of the swivel butt type, the webs or flanges 20 and 23 are preferably depressed or cut-away beneath the cut-away portions 38 of the carrier block as indicated at 42. Inasmuch as the width of the supporting plate 31 preferably corresponds with the width of the tie portion 22, the side flanges or webs 20 and 23 are preferably outwardly bowed as indicated at 43 to surround or embrace the 65 ends of said plate, and above said plate they are

retained at approximately the same distance apart or slightly less as indicated at 44, so that they closely embrace the ends of the block 29 with merely normal clearance provided. It will be seen that the upper portions of the webs 44 5 above the bulges 43 serve to properly position the wear plate 41 by closely approaching the ends thereof.

From the foregoing description of my invention it will be clear that the carrier block 29 10 may be assembled with the sill tie casting 15 as follows. The enlarged butt of the coupler 11 is first inserted beneath the striking casting 5 and above the depressed or cut-away portion 42 of the sill tie casting 15 and the minimum section 15 of the stem moved to an upper corner of the opening therebetween, after which the carrier block 29 is inserted through one of the apertures 32 and moved upwardly and diagonally until the lower end rests on one of the ledges or 20 extensions 30 after which it may be moved to horizontal position resting on said ledges 30. While the coupler is still in elevated position, the wear plate 41 is applied and the block and wear plate together are raised just enough to 25 receive the supporting plate 31 beneath said block, said plate being thereafter locked in position by the cotter or the like 33 and the coupler 11 thereupon allowed to rest upon the wear plate and block therebeneath. Said block may be removed while the coupler is in place in the opposite manner as will be understood.

The webs 6 and 16 are constructed so as not to approach each other near enough to interfere with the slots 45 in the sills for receiving associated draft keys indicated at 46. As is usual, cheek plates 47 are applied to said sills and correspondingly slotted. In the present embodiment, the cheek plates are applied to the opposite sides of the webs 2, that is, to the outer surfaces of said 40 webs, and the rearmost rivets 7 and 17 preferably serve as common rivets for connecting the webs 6 and 16, the sill webs 2 and the cheek plates 47.

Referring now to the embodiment of my invention illustrated in Figures 4, 5, and 6, a construction is there disclosed involving a striking casting 5^a which may be identical with the casting 5 of the first embodiment and be connected to the sills 1^a in a similar manner. The construction of the present embodiment is also particularly 50 adapted for use with a coupler 11^a having an enlarged butt specifically illustrated as of the swivel butt type.

Connected beneath the sills 1^a, as in the previous embodiment, is a sill tie casting 15^a provided with webs 16^a and 18^a corresponding with the webs 16 and 18 of the previous embodiment, and connected to the sills by rivets 17^a and 19^a respectively. The sill tie portion 22^a preferably comprises a pair of vertical transverse webs 20^a and 23^a connected by a horizontal web 24^a rigidified by an upstanding flange 25^a, the upper edge of which is flanged as indicated at 30^a to provide an abutment for one end of the carrier block 29^a. The ends of the flanges 20^a and 23^a are also preferably connected by webs 48 extending from the ends of the webs 18^a. As in the previous embodiment, the central portions of the webs 20^a and 23^a are depressed or cut-away as indicated at 42^a to facilitate insertion and removal of the swivel butt of the coupler 11^a.

In the present embodiment, the carrier block 29^a has an upper web 39^a upwardly off-set as indicated at 40^a and receiving a wear plate 41^a. Said block also has side webs or flanges 37^a up- 75

wardly bowed or cut-away at intermediate portions thereof as indicated at 38^a, the end webs 36^a are provided with outstanding flanges 49, one of which normally rests on the abutment 30^a, 5 and the other on a retainer or removable support 50, preferably rectangular in section and received in pockets 51 and 52 in the webs 23^a and 20^a respectively. The retainer 50 is preferably adapted for insertion and removal from the outer 10 end only so that the pocket 51, although provided with an aperture 53 for inserting a tool to facilitate removal of the retainer, is not adapted to permit removal thereof from that side. The pocket 52 has an outer opening 54 normally 15 closed by a cotter or like locking means 55 to prevent an undesired removal of the retainer 50. The flange or web 25^a is omitted at the end of the sill tie portion 22^a adjacent the retainer 50, so that when said retainer is removed, an aperture 20 56 is provided sufficient in size for allowing removal or insertion of the carrier block 29^a in a manner similar to that described in connection with the carrier block 29 of the first embodiment. As in the previous embodiment, the sides of the 25 sill tie portion 22^a are extended upwardly a sufficient distance so that their upper ends are preferably normally flush with the ends of the carrier block 29^a where they closely approach the ends of the wear plate 40^a, as shown at 44^a, and 30 retain the same in proper position. Except as specifically described in connection with the present embodiment, the same may correspond with the first embodiment.

Referring now to the embodiment of my invention illustrated in Figures 7 and 8, a modified retainer 50^b for one end of a corresponding carrier block 29^b is illustrated. Said retainer is shown round in section rather than rectangular and headed at one end as indicated at 57, either 35 being retained in place by a cotter or the like 55^b, as in the first embodiment, or by a cotter or the like (not shown) through an aperture 58 in the opposite end. The head 57 also preferably fits in a notch 59 in an extension from the web 40 45 of the sill tie casting 15^b, so that said retainer 50^b is practically self-locking as in the embodiment of Figures 4, 5 and 6.

From the foregoing disclosure, it will be apparent that I have devised a coupler carrier and 50 associated striking casting which are adapted to leave an aperture therebetween sufficient in size for receiving an enlarged butt or the swivel butt of an associated coupler, when the associated carrier block is not in place. When, however, the 55 carrier block is positioned beneath the stem of the coupler, which is readily accomplished while the coupler is in place by insertion through an aperture provided in the lower portion of the sill tie casting, said coupler is supported in proper 60 position with only normal clearance between it and the associated striking casting thereabove. It will be seen that in each of the first two embodiments illustrated a rectangular or flat retainer is insertable beneath the carrier block and 65 rests on ledge means for supporting said block while closing an opening in the bottom of the tie casting to prevent removal of the block as long as the associated coupler is in place.

Having now described my invention, I claim: 70

1. In combination with the draft sills of a car, a striking casting, a sill tie casting, a coupler with a stem positioned therebetween, and formed with an enlarged butt, said castings being formed with side portions connected to the webs of the sills, said sill tie casting being formed with a tie por-

tion spaced sufficiently from the striking casting to permit the free insertion and removal of said enlarged butt, a removable carrier block supported on the sill tie casting, and retainer means supporting said block, so that it will support the 5 stem with the desired amount of clearance between it and the striking casting, and when removed permitting removal or insertion of said block from below the tie casting.

2. A sill tie casting formed with side portions 10 adapted for connection inside of the webs of draft sills of a car below a striking casting thereon for supplementing said striking casting so that said castings together function as a combined striking casting and sill tie, said casting having web portions for directly supporting a carrier block and apertured to receive the same for permitting the application and removal of said block from below.

3. A sill tie casting formed with upstanding sides adapted for connection with the webs of 15 associated draft sills beneath a striking casting thereon, said casting being formed with a tie adapted to be spaced sufficiently from the striking portion of the casting to permit the free insertion and removal of the enlarged butt of a 20 coupler, a removable carrier block supported on the sill tie portion, said sill tie being formed with an aperture permitting the insertion and removal of the block from below while the associated 25 coupler is in place.

4. A sill tie casting formed with upstanding sides adapted for connection with the webs of 30 associated draft sills and horizontal webs extending therefrom and adapted for connection with the lower flanges of said sills, said casting 35 having a tie portion normally spaced sufficiently from an associated striking casting to permit the free insertion and removal of the enlarged butt of a coupler, and a removable carrier block supported on said sill tie portion and with its top 40 surface normally disposed a substantial distance above the top of the tie portion so as to partially close the enlarged opening thereabove and support the coupler stem in proper position.

5. A sill tie casting formed with webs adapted 45 for connection with associated draft sills, and a tie portion between said webs, the central part of said tie portion being depressed to facilitate the insertion and removal of an associated coupler with an enlarged butt, said tie portion being 50 formed with ledge means serving to support an associated carrier block, a carrier block supported thereon and retainer means serving to prevent undesired removal of said block, the lower outline of said block being bowed upwardly 55 between the ends to facilitate insertion and removal thereof from below.

6. A sill tie casting formed with webs adapted 60 for connection with associated draft sills, a tie portion connecting said webs and comprising vertical transverse webs and a horizontal web connecting the lower portions thereof, a carrier block supported on said casting and retainer means for preventing undesired removal thereof, the horizontal web of said tie portion being 65 omitted for a portion of the length thereof to permit insertion and removal of the carrier block with the associated coupler thereabove.

7. A sill tie casting formed with webs adapted 70 for connection with associated draft sills and a tie portion between said webs, said tie portion being formed with ledge means serving for the support of an associated carrier block, and a flat retainer member insertable beneath said carrier 75 block and resting on said ledge means for sup-

porting said block, said retainer closing an opening in the bottom of the tie casting to prevent removal of said carrier block while the associated coupler is in place.

5 8. A carrier block adapted for support beneath the stem of an associated coupler on a sill tie casting and having an upper supporting web depending side webs, and downwardly and outwardly diverging end webs, said side webs adjacent the center of the block having their lower edges bowed upwardly to decrease the weight of said block and the depth at the center thereof and facilitate insertion and removal.

10 9. A carrier block adapted for support beneath the stem of an associated coupler on a sill tie casting and having an upper supporting web, depending side webs, downwardly and outwardly diverging webs connecting the ends of said side webs and depending from the ends of said upper web, and flanges extending outwardly from the lower portions of said end webs and adapted to rest on abutment portions of the sill tie casting.

15 10. A sill tie casting formed with upstanding sides adapted for connection with the webs of

20 associated draft sills and formed with a tie portion adapted to be positioned to permit the free insertion and removal of the enlarged butt of a coupler thereabove, and a removable carrier block directly supported at one end on a portion of the sill tie casting and at its other end on a retainer, said retainer, when removed, leaving an aperture through the sill tie casting adapted to permit insertion and removal of the carrier block from below.

25 11. The combination with a car coupler having an enlarged butt, of a coupler carrier secured to the car body and extending under the coupler, the portion of said carrier which underlies the coupler being spaced vertically downward from the overlying portion of the car body to permit passage of the enlarged coupler butt while said carrier is in assembled position and comprising longitudinally spaced walls and a detachable bottom member and means normally supported by said bottom member for maintaining the coupler in vertically spaced relation to the portion of said carrier underlying said coupler, said bottom member being adapted to be lowered between said walls to permit the passage of said enlarged coupler butt.

30 12. The combination with a laterally swinging car coupler, of a coupler carrier secured to the car body and extending under the coupler, said underlying portion of the carrier being formed with longitudinally spaced walls, a downwardly removable coupler support disposed between said spaced walls and normally extending above the latter, and means connected to said walls and extending under said coupler support for maintaining the latter in assembled position.

35 13. The combination with a car coupler having an enlarged butt, of a coupler carrier secured to the car body and extending under the coupler, the portion of said carrier which underlies the coupler being spaced vertically downward from the overlying portion of the car body to permit passage of the enlarged coupler butt while said

carrier is in assembled position and being formed with transversely extending walls which are spaced from each other longitudinally of the car, and means positioned between said walls for normally maintaining the coupler in vertically spaced relation to said walls, said means being adapted to be lowered between said walls to permit the passage of said enlarged coupler butt.

40 14. In combination with the draft sills of a railway vehicle, a coupler having a stem disposed between said sills and provided with an enlarged butt, a striking casting connecting said sills and overlying said stem, and a coupler carrier connecting said sills and underlying said stem, that portion of said carrier directly beneath said stem being spaced vertically downward from said striking casting a distance sufficient to permit passage of the enlarged butt, a block supported by said carrier for maintaining the coupler at a desired level above the underlying portion of the carrier, said block being adapted to be lowered between portions of said carrier to permit the passage of said enlarged butt beneath said striking casting.

45 15. In combination with the slotted draft sills of a railway vehicle, a coupler having a stem disposed between said sills and provided with an enlarged slotted butt, a slotted yoke disposed between said sills, a key received in the slotted portion of said sills, butt and yoke for connecting said coupler and yoke, the slotted portions of sills being framed by cheek plates connected to the outer surfaces of said sills, a striking casting connecting said sills, overlying said stem, and with portions on the inner sides of said sills overlapping portions of said cheek plates, and a coupler carrier connecting said sills, underlying said stem, and with portions on the inner sides of said sills overlapping portions of said cheek plates, common means connecting said overlapping striking casting and cheek plate portions to the sills therebetween, other common means connecting said overlapping coupler carrier and cheek plate portions to the sills therebetween, that portion of said carrier directly beneath said stem being spaced vertically downward from said striking casting a distance sufficient to permit passage of the enlarged butt, and a block supported by said carrier for maintaining the coupler at a desired level above the underlying portion of the carrier.

50 16. In combination with the draft sills of a car, a striking casting, a sill tie casting formed with upstanding side portions provided with rearwardly extending side webs disposed beneath portions of the striking casting and connected to the sills, said webs being positioned so as not to interfere with slots in the sills for receiving a draft key, and cheek plates connected to the other sides of said sills, correspondingly slotted and formed with portions extending forwardly of, overlapping the ends of said side webs and corresponding portions of the striking casting, connected to said sills and side webs by common means, and connected to said sills and striking casting by other common means.

DONALD S. BARROWS.
